ARTHUR TREVOR DAWSON AND GEORGE THOMAS BUCKHAM, OF WESTMINSTER, ENGLAND, ASSIGNORS TO VICKERS SONS & MAXIM, LIMITED, OF WESTMINSTER, ENGLAND.

FIELD GUN-CARRIAGE.

SPECIFICATION forming part of Letters Patent No. 733,166, dated July 7, 1903.

Application filed September 5, 1902. Serial No. 122,217. (No model.)

To all whom it may concern:

Be it known that we, ARTHUR TREVOR DAWSON, lieutenant of the Royal Navy and director and superintendent of ordnance-works, and GEORGE THOMAS BUCKHAM, engineer, subjects of the King of Great Britain, both residing at 32 Victoria street, Westminster, in the county of London, England, have invented certain new and useful Improvements in and Relating to Field Gun-Carriages, of which the following is a specification.

This invention relates to field carriages or mountings chiefly designed for howitzers.

The said invention has reference to the elevating-gear, which is constructed to enable the howitzer to be readily and quickly moved through large angles of elevation for permitting it to be brought rapidly to loading position when firing at extreme angles of elevation.

We will now describe our invention with reference to the accompanying drawings, in which—

Figure 1 is a side elevation, Fig. 2 a plan, and Fig. 3 a rear end view, of a howitzer and its carriage constructed in accordance with our invention, one of the carriage-wheels being removed in Fig. 1. Fig. 4 is a front elevation, and Fig. 5 a vertical section taken approximately on the line 1 1 of Fig. 4, showing a portion of the elevating-gear on an enlarged scale. Fig. 6 is a side elevation of the carriage, showing a modified form of the elevating-gear and also showing the spade carried by the forward part of the trail.

In all the figures like letters of reference indicate similar parts.

A is the howitzer. B is the cradle in which it recoils.

C is the trail.

The elevating-gear comprises an elevating arm d, Figs. 4 and 5, pivoted to a bolt d', screwed into the left-hand trunnion b of the cradle B, the said trunnion being prolonged through the bearing for this purpose. The said elevating-arm is attached by a pivot-pin d² and a connecting-rod d³ to the elevating-gear of the ordinary screw pattern provided with the actuating hand-wheel D. At the

outer or free end of the elevating-arm d a screw-clamp d³ is provided, by means of which the said arm may be fixed at any angle of elevation upon a slotted quadrant or clamping-arc d⁴, secured to the trailside. The outer end b⁵ of the said trunnion extension is of octagonal or other suitable form to receive a bell-crank lever, one arm, B⁶, of which forms a long rearwardly-extending handle, while the other arm, b⁷, carries a spring-bolt b⁸, by means of which the gun is locked to the elevating-arm d and through said arm to the elevating-gear worked by the hand-wheel D. An incline is cut on a projection d⁹ of the elevating-arm d, by means of which the bolt b⁸ is automatically pushed in as the howitzer is returned angularly to its firing position, so that the said bolt can under the action of its spring reengage with the elevating-arm and lock the howitzer at the proper angle of elevation. A stop d¹⁰ is also provided on the elevating-arm d in a position to relieve the bolt b⁸ from the lateral stress it would otherwise experience as the howitzer is brought suddenly to rest in returning to its firing position by actuating the aforesaid long handle B⁶. The howitzer is elevated by the hand-wheel D in the usual manner, and the elevating-gear is clamped in position by turning the screw-clamp d³. Then to bring the gun quickly to the loading position a push-piece in the form of a small lever d¹¹ on the elevating-arm d is pressed inward, thereby bringing a nose d¹² thereof against the spring-bolt b⁸ and by forcing the latter inwardly unlocking the howitzer, so that it can be quickly brought to the loading position by the handle B⁶ independently of the elevating-arm d. After loading the said howitzer can quickly be returned to firing position, where it is automatically locked again to the elevating-arm d by the spring-bolt b⁸ reengaging with the elevating-arm. It will thus be seen that after the elevating-gear is once set for any desired angle of elevation it is unnecessary to again operate it unless the angle of elevation is to be varied. We thus insure increased rapidity in firing.

In some instances, as in the example illus-

trated by Fig. 6, we make the clamping-arm d^4 in one piece with the elevating-arm d and fix the screw-clamp d^3 to the side of the trail.

What we claim, and desire to secure by Letters Patent of the United States, is—

1. In a field gun-carriage, the combination with the gun and its cradle, of an elevating-arm pivotally connected with one of the cradle-trunnions, gear for operating said arm, an actuating-handle fixed to said trunnions, and means for readily locking and unlocking said actuating-handle to and from said elevating-arm, substantially as and for the purpose specified.

2. In a field gun-carriage, the combination with the gun and its cradle, of an elevating-arm pivotally connected with one of the cradle-trunnions, gear for actuating said arm, a bell-crank lever fixed to said trunnions and provided with a rearwardly-extending handle, and means for readily locking and unlocking said bell-crank lever to and from said elevating-arm substantially as and for the purpose specified.

3. In a field gun-carriage, the combination with the gun and its cradle, of an elevating-arm pivotally connected with one of the cradle-trunnions, gear for actuating said arm, means for locking said arm in its angularly-adjusted position, a bell-crank lever fixed to the said trunnion and provided with a rearwardly-extending handle, and means for readily locking and unlocking said bell-crank lever to and from said elevating-arm substantially as and for the purpose specified.

4. In a field gun-carriage, the combination with the gun and its cradle, of an elevating-arm pivotally connected with one of the cradle-trunnions, gear for actuating said arm, a clamp on said arm, a fixed slotted segment in which said clamp works and to which said arm is adapted to be fixed by the clamp, a bell-crank lever fixed to the aforesaid trunnion and provided with a rearwardly-extending handle, and means for readily locking and unlocking said bell-crank lever to and from said elevating-arm, substantially as and for the purpose specified.

5. In a field gun-carriage, the combination with the gun and its cradle, of an elevating-

arm pivotally connected with one of the cradle-trunnions, gear for actuating said arm, means for locking said arm in its angularly-adjusted position, a bell-crank lever fixed to the said trunnions and provided with a rearwardly-extending handle, a spring-bolt for locking said bell-crank lever to said elevating-arm and means for liberating said spring-bolt when the bell-crank lever is to be operated independently of the elevating-arm substantially as and for the purpose specified.

6. In a field gun-carriage, the combination with the gun and its cradle, of an elevating-arm pivotally connected with one of the cradle-trunnions, gear for actuating said arm, means for locking said arm in its angularly-adjusted position, a bell-crank lever fixed to the said trunnion and provided with a rearwardly-extending handle, a spring-bolt on the bell-crank lever for locking the latter to said elevating-arm, and a push-piece on the elevating-arm for disengaging the spring-bolt from the elevating-arm substantially as and for the purpose specified.

7. In a field gun-carriage, the combination with the gun and its cradle, of an elevating-arm pivotally connected with one of the cradle-trunnions, gear for actuating said arm, means for locking said arm in its angularly-adjusted position, a bell-crank lever fixed to the said trunnion and provided with a rearwardly-extending handle, a spring-bolt on the bell-crank lever for locking the latter to said elevating-arm, a push-piece on the elevating-arm for disengaging the spring-bolt, an incline on the elevating-arm for actuating said spring-bolt as the elevating-arm returns to its position of reengagement with the spring-bolt, and a stop on the elevating-arm to relieve the spring-bolt from lateral stress as the parts are returned to firing position substantially as and for the purpose specified.

In testimony whereof we have hereunto set our hands, in presence of two subscribing witnesses, this 26th day of August, 1902.

ARTHUR TREVOR DAWSON.
GEORGE THOMAS BUCKHAM.
